BY

James D. Hardisty

ATTORNEY.

UNITED STATES PATENT OFFICE.

ROLAND P. PLACE, OF MIDLAND, MICHIGAN.

HOOD CATCH.

Application filed February 4, 1926. Serial No. 85,890.

The present invention relates to hood door latches particularly for securing the sides of the hood which covers the engine of an automobile and has among its objects an improved latch which efficiently holds down the hood member and at the same time prevents the lateral movement which is usually accompanied by rattling.

Another object is a latch which is simple in construction and design, economical to produce, and difficult to get out of order.

With these and other objects in view, as will more readily appear to those skilled in the art, the invention consists in the improved latch illustrated in the accompanying drawing, described in the following specification, and particularly claimed in the concluding claims; and in such variations and modifications thereof, within the scope of the claims, as will be obvious to those skilled in the art to which the invention relates.

Reference should be made to the accompany drawing, in which:

Fig. 1 is an elevation, partly in section, of the latch and co-operating parts of an automobile hood;

Fig. 2 is an elevation from the right of Fig. 1;

Fig. 3 is a view similar to Fig. 1, but showing the latch unfastened.

In the drawings, the free edge of the hood door which is to be held by the latch is indicated at 5 and the sill, against which the latch holds it, as 6, 7 being the frame member carrying the latch and sill, the hood, sill and frame being all of conventional construction.

Secured to member 7 as by a threaded stud 9 and nut 10, is a fixed pivotal support 8 for the latch, which comprises a spring arm 11, preferably of flat stock, carrying at its free end a door engaging block or pad 12, preferably of rubber, adapted to press the hood 5 against the sill 6 when in latched position and thereby secure it against lateral movement.

Spring arm 11 has at its other end lateral arms 15 bent downwardly to U-shape and embracing the support 8 to which they are pivotally secured by a suitable rivet or bolt 16.

The latch proper or hold-down member consists of a tubular portion 20 flanged inwardly at its lower end as at 21 and provided at its upper end with a head 22 which latter is extended toward the hood and formed with

a hook 23 adapted to hook over a fixed abutment or stirrup 24 carried by the hood 5. Head 22 is also extended away from hood 5 to form a suitable handle 25 by which the latch may be operated.

Inside of tubular portion 20 is a compression spring 30 seated against flange 21 and surrounding a bolt 31 whose head rests upon the upper end of the spring 30 and is adapted to slide in tube 20. The lower end of bolt 31 passes out of the lower end of tube 20 and through spring member 11 and the whole is secured together by a nut 32 on the end thereof and also embraced by the U-shaped end of the member 11, the bolt 31 forming a stem upon which the hold-down member is movable longitudinally.

As indicated, when the latch is lifted and moved toward the hood so as to drop hook 23 over abutment 24, arm 11 will be pressed against the hood 5 and the latter thereby pressed tightly against sill 6, while the hook 23 holds the hood down.

Having now described the invention and the preferred form of embodiment thereof, it is to be understood that said invention is not to be limited to the specific details herein described and illustrated but only by the scope of the claims which follow.

I claim:

1. A hood door latch of the class described comprising a spring arm having a door engaging block at its upper end, and the lower end of which is pivotally connected with a fixed support; a stem fixedly secured to said arm adjacent the lower end thereof and extending upwardly from said lower end alongside said arm; and a spring actuated hold-down member carried by said stem and movable longitudinally thereupon and having a hook adapted to engage a fixed abutment carried by a hood door.

2. A hood door latch comprising a tubular member provided with a head including a hook adapted to cooperate with an abutment on the hood door to hold down the latter, a compression spring within the tubular member and resting on an inwardly extending flange formed at the lower end thereof, a stem within said spring and having a head resting thereon, said stem extending from the lower end of said member, means for pivotally securing said latch to a fixed frame member, said stem extension being secured to

said securing means, and a resilient arm extending from said securing means, said arm being constructed and arranged to press said hood door away from said latch when the latter is in latched position.

3. A hood door latch comprising a resilient sheet metal member having at one end a com-

pressible block or pad and formed at its other end to U-shape whereby to embrace a pivotal mounting post, a stem secured to said U-shaped end, a tubular latch member mounted to slide longitudinally on said stem, and a spring to resist said sliding.
